UNITED STATES PATENT OFFICE.

THEODORE HAVILAND, OF AMBAZAC, FRANCE.

DESIGN FOR A COVERED DISH.

SPECIFICATION forming part of Design No. 23,775, dated November 6, 1894.

Application filed October 12, 1894. Serial No. 525,729. Term of patent 7 years.

To all whom it may concern:

Be it known that I, THEODORE HAVILAND, a citizen of the United States, residing at Am-
bazac, in the Department of Haute-Vienne and
5 Republic of France, have invented and pro-
duced a new and original Design for Dishes;
and I do hereby declare the following to be a
full, clear, and exact description of the same,
reference being had to the accompanying
10 drawings, forming a part thereof.

The principal feature of my design consists
in a covered dish the lower part of which and
the outer edge of the cover are ornamented
with shell and scroll like work in relief, and
15 having handles of the same general design.

Figure 1 represents a side view of the dish,
and Fig. 2 a face view of the cover.

In Fig. 1 the scroll like work appears to rise
from the base of the dish and reach upward

in irregular projections toward the center A. 20
The handles B B, at either end of the dish and
the center of the cover, simulate heavy scrolls
with ornamentations of sea plants at the
points where they join the dish. Fig. 2 repre-
25 senting a face view of the cover, the scroll
work commences at the outer edge or rim and
extends a short distance toward the center of
the cover in the same general way as described
in the body of the dish.

What I claim is—

The design for dishes substantially as here-
in shown and described.

In testimony whereof I affix my signature in
presence of two witnesses.

THEODORE HAVILAND.
